UNITED STATES PATENT OFFICE.

ALBERT A. PAGE, OF EAST HAVEN, CONNECTICUT, ASSIGNOR TO SARGENT & COMPANY, OF NEW HAVEN, CONNECTICUT, A CORPORATION OF CONNECTICUT.

LOCK.

1,195,713.

Specification of Letters Patent. Patented Aug. 22, 1916.

Application filed April 10, 1916. Serial No. 90,156.

To all whom it may concern:

Be it known that I, ALBERT A. PAGE, a citizen of the United States, residing in East Haven, in the county of New Haven 5 and State of Connecticut, have invented certain new and useful Improvements in Locks, of which the following is a full, clear, and exact description.

This invention relates to locks, and more 10 particularly to locks of the mortise type in which a latch bolt is adapted to be retracted by key mechanism at the outside of the door, and by knobs at the inside and outside of the door respectively, there being suitable 15 stop work associated with the outside knob for dogging it when it is desired to confine the retraction of the bolt from the outside to the key mechanism.

The invention also has special reference 20 to a lock in which the stop mechanism comprises dogging and releasing slides respectively operating in openings of the face plate.

The invention is of utility, however, in 25 connection with locks of different types.

One of the primary objects of the invention is to provide improved means for controlling the stop work, so that when it is in the dogging position it cannot be cast off 30 from the face of the lock by a speak thief when the door is open, or by a burglar when the door is closed.

Another object of the invention is to provide a lock having means for preventing the 35 throwing off of the stop work except when one of the latch retracting levers is operated, said means being so constructed that it is applicable to a lock having a very narrow backset.

40 To these and other ends, the invention consists in the novel features and combinations of parts to be hereinafter described and claimed.

In the accompanying drawing, Figure 1 is 45 an elevation of a lock embodying my improvements, with the cap plate removed, the latch bolt being in the normal protracted position; Fig. 2 is a similar view, showing the latch bolt retracted, and the stop work 50 released for manual operation from the face of the lock; and Fig. 3 is a section on line 3-3 of Fig. 1.

In the drawings, I have shown my improvements applied to a mortise lock having 55 a very narrow backset. The case 3 of usual

pattern contains a latch bolt 4, having a stem 5 guided between lugs 6, 7 on the back of the case. A spring 8 embracing the latch bolt stem between the head and the lugs 6, 7 normally holds the bolt in protracted position. A cross-head 9 on the rear end of the latch bolt stem rests back of the upwardly extending arm of a latch retracting lever 10, pivoted in the lower portion of the case on a post 11, and adapted to be actuated by an inside hub 12 or an outside hub 13. These hubs are associated with the usual two-part knob spindle, which I have not considered it necessary to illustrate. The hubs 12, 13 are adapted to act on the 60 lever 10, through a shorter lever 14, located underneath the lever 10, and pivoted on the same post 11, said lever 14 having a flange 15 adapted to make contact with lever 10 when either hub is turned in a clockwise direction with respect to Fig. 1, whereby the lever 10 is actuated to retract the latch bolt, as shown in Fig. 2. The lever 10 may be actuated from the outside of the door by suitable key mechanism which may comprise a cylinder lock 16, having a rollback or cam arm 17 to engage the upper extremity 18 of the latch retracting lever 10, as indicated by the dotted lines in Fig. 2.

The stop work mechanism associated with 85 the outside hub 13 comprises a dogging slide 19, adapted to engage a notch 20 in the hub 13, and a releasing slide 21 connected with the dogging slide by a walking beam member 22, pivoted in the case at 23, and pivoted to the releasing slide 21 at 24. The lower end of the walking beam is provided with a notch 25 fitting over a pin 26 on the dogging slide 19. A lever 27, pivoted in the case at 28, and acted on by a spring 29, 90 is pressed upward by its spring into such a position that a projection 30 on the upper edge portion of the lever 27 extends into the notch 25 of the walking beam when the stop work is in the position shown in Fig. 1. In 100 this manner, the lever 27 dogs the lower end of the walking beam member and prevents movement to the left with reference to Fig. 1, such as is necessary to release the dogging slide from the outside hub when the releasing slide is pushed inward. It will be understood, therefore, that under normal conditions the lever 27 dogs the stop work when the latter is in the operative position.

When it is desired to release the outside 105

hub, the lever 10 is actuated by turning the inside knob, which causes the inside hub 12 to actuate the lever 10 through the lever 14, as shown in Fig. 2. As the lever 10 is actuated, a nose portion 31 on said lever projecting downward beyond the pivotal portion of the lever engages the extremity 32 of the lever 27 and turns said lever 27 on the pivot 28 into a position in which the 10 projection 30 on the dogging lever will release the walking beam, as shown in Fig. 2. The stop work can then be cast off in the usual manner by pressing inward the releasing slide 21. The walking beam is then 15 moved to the position shown in dotted lines in Fig. 2, the dogging slide being carried out of engagement with the outside hub. On releasing the inside knob, the dogging lever will move back to its initial position, the 20 projection 30 thereof being then located slightly to the rear of the lower portion of the walking beam member. The stop work may be moved into the dogging position without the necessity of actuating the lever 10, because as the dogging slide is pushed 25 inward the lower end of the walking beam member pushes the projection 30 of the dogging lever out of the way. Then, when the dogging slide has reached the dogging position, the projection 30 snaps up into the 30 notch in the lower end of the walking beam and again dogs the stop work.

The lock is readily reversible because the latch bolt may be reversed, the cylinder 16 may be inserted in an opening at either side of the case, and the hubs 12, 13 may be interchanged. The inner end of the dogging slide 19 is wider than the hub 13 and will engage the notch in said hub when the lock 40 is reversed, as well as when the parts are in the adjustment shown.

Various changes in the details of the construction may be adopted without departing from the scope of the invention as defined in the claims.

What I claim is:—

1. In a lock, a latch bolt, inside and outside hubs, dogging mechanism for the outside hub, a lever adapted to be actuated by 50 said hubs for retracting said bolt, key mechanism for retracting said bolt by said lever, and means to dog said dogging mechanism

as long as it dogs said outside hub, said means releasable by said lever when the latter is actuated by the inside hub; substantially as described. 55

2. In a lock, a latch bolt, inside and outside hubs, stop work associated with the outside hub, and including dogging and releasing slides respectively, a lever adapted 60 to be actuated by said hubs to retract said bolt, and means normally dogging said dogging slide against releasing movement at any time when said slide occupies its operative position, said means being operative when the door is open as well as when it is closed, and being releasable only by the actuation of said lever by the inside hub; substantially as described. 65

3. In a lock, a latch bolt, inside and outside hubs, means for retracting said bolt by said hubs, stop work associated with the outside hub and including dogging and releasing slides respectively, and a walking beam member interconnecting said slides, a 70 lever for engaging said walking beam member to dog the stop work, and means for shifting said lever out of its dogging position to release the stop work; substantially 75 as described. 80

4. In a lock, a latch bolt, inside and outside hubs for retracting the same, said outside hub having a notch therein, a dogging slide having a portion to engage said notch, the dogging portion of said slide being of 85 greater width than the outside hub so that said slide will dog said hub when the hubs are interchanged to reverse the hand of the lock, and means for dogging the dogging slide against movement from its dogging position; substantially as described. 90

5. In a lock, a latch bolt, inside and outside hubs, a lever for retracting said bolt by means of said hubs, a dogging slide for engaging the outside hub, a releasing slide, a 95 walking beam connecting said dogging slide with said releasing slide, and a spring pressed dogging lever for engaging said walking beam controlled by said bolt retracting lever; substantially as described. 100

In witness whereof, I have hereunto set my hand on the 7th day of April 1916.

ALBERT A. PAGE.
